UNITED STATES PATENT OFFICE.

JAMES LACHLIN WEIR, OF CHATHAM, ONTARIO, CANADA.

DESIGN FOR A COLLAR-SPACER.

46,151.

Specification for Design.

Patented July 21, 1914.

Application filed March 2, 1914. Serial No. 822,068. Term of patent 7 years.

To all whom it may concern:

Be it known that I, JAMES LACHLIN WEIR, a subject of the King of England, residing at Chatham, in the Province of Ontario and Dominion of Canada, have invented a new, original, and ornamental Design for Collar-Spacers, of which the following is a specification, reference being had to the accompanying drawing, forming part thereof.

The figure is a perspective view of a collar spacer, showing my new design.

I claim:

The ornamental design for a collar spacer as shown.

JAMES LACHLIN WEIR.
